UNITED STATES PATENT OFFICE.

SQUIRE FIELDER, OF ELIZABETHTOWN, INDIANA.

FENCE-POST.

SPECIFICATION forming part of Letters Patent No. 734,690, dated July 28, 1903.

Application filed April 18, 1903. Serial No. 153,193. (No model.)

To all whom it may concern:

Be it known that I, SQUIRE FIELDER, of Elizabethtown, Bartholomew county, Indiana, (post-office address the same,) have invented 5 certain new and useful Improvements in Fence-Posts, of which the following is a specification.

My invention pertains especially to an end or corner post for wire fences, the essential 10 features of which consist of a post placed on the ground, not partially buried therein, which is braced with tension-rods in such a way as to effectually resist the pull of a wire fence.

15 My invention consists in the following combination of elements as hereinafter described and claimed.

In the drawings, Figure 1 is a perspective view of my improved post, showing a hole cut 20 in the ground to expose the anchor-timbers; Fig. 2, a cross-section on line A A, and Fig. 3 a detail of a portion of my invention.

The numeral 1 represents a post, preferably 25 of gas-pipe, which is supported by a suitable foundation built on the ground. Said post may rest directly on the ground, if desired. A brace 2 is secured to post 1 at a point near its upper end by any suitable means, such as a bolt 3. The lower end of brace 2 is bent 30 so as to be in the same plane as the bottom of the post and rests upon a rock or other suitable support. A tension-rod 4 is hooked through a hole 5 in brace 2 at a point close to the lower end of said brace and passes 35 back through post 1 at a point near its lower end and is provided with a threaded nut 6, so that said rod can be put under any desired tension.

Hooked into the lower end of post 1 are two 40 tension-rods 7, diverging both outwardly and

downwardly from said post 1 and secured to a timber 8 or other suitable anchorage buried in the ground. It will be seen that the post will be held rigidly in position by means of this bracing and is capable of resisting a pull 45 in the direction of brace 2.

As an additional side brace to support the post against lateral strains I provide braces 9, which are bent at their upper ends 10, as shown, to both form a hook and stay. Said 50 braces hook into the post at any suitable distance from the ground. By bending the upper ends 10 of braces 9 I am enabled to get a tension-brace having a certain degree of lateral leverage on the upper end of the post, 55 and at the same time I provide a connection to resist a tension which will not pull out. The lower ends of braces 9 are secured to any desirable anchorage.

I claim as my invention—

In a fence-post the combination of a main post, 1, a brace, 2, secured to post, 1, at a point near its top, and extending outwardly and downwardly therefrom; an adjustable tension-rod 4, secured to the outer end of 65 brace 2, and to post, 1, near its lower end; braces 7, secured to the lower end of post, 1, and diverging outwardly and downwardly therefrom, said braces, 7, secured to a suitable anchorage, 8; lateral braces, 9, bent at 70 their upper ends to form a hooked offset 10, secured to post, 1, said braces diverging outwardly and downwardly and secured to a suitable anchorage, substantially as and for the purpose set forth.

SQUIRE FIELDER.
